UNITED STATES PATENT OFFICE.

CHARLES H. WILD, OF BALTIMORE, MARYLAND, ASSIGNOR TO BURT MACHINE COMPANY, INCORPORATED, OF BALTIMORE, MARYLAND, A CORPORATION OF MARYLAND.

CAN-LABELING MACHINE.

Application filed May 5, 1926. Serial No. 106,885.

The invention relates to machines for labeling cans or cylindrical packages of the type in which the cans are passed through the machine by rolling along a runway or ways. The labels are placed beneath the runway in a pack from which they are removed successively by the cans as they pass, the label which is on top in each instance being picked up, i. e., caused to adhere to the can as it rolls over it, by means of the paste or cement which holds the label, or more correctly the near or forward end of the label in its final position on the can, the far end or lap end of the label being secured by adhesive applied by separate means from a separate source. The terms near and far and upward and rear have reference to the position of the labels in the machine, the front of the machine being the point at which the cans are fed into it.

The present invention relates primarily to a machine in which the adhesive which secures the forward end of the label to the can is applied directly to the label. The can as it passes rolls over the label and the paste coated forward end of the label, sticks to the can winding or rolling the label about the can as the latter advances. Adhesive for the lap end is separately applied as already outlined.

The object of the invention is to provide improved means for applying the adhesive and controlling the same by the passing cans, so that the adhesive is affixed to the labels at the instant they are placed on the cans preventing premature drying of the adhesive and making regular feeding nonessential. As each label is picked up and the next label beneath is exposed the pasting mechanism is made ready for application of adhesive to the newly exposed label so that there is no opportunity for the paste to dry on the label and the can which is next to pass operates the mechanism for applying adhesive to the label so that each label when picked up by the can is freshly coated with adhesive.

In previous machines of this type difficulty has been encountered due to the tend-

ency of the adhesive to dry on the labels so they do not stick to the can. Also the paste accumulates on the belts, rollers and labels, by and to which it is applied, giving the label an irregular, bumpy, smeared and unsightly appearance. This difficulty is entirely overcome in the present machine in which the paste applying means is tripped by the cans as they pass and operates for a short period only. This applies not only to the pick-up pasting mechanism, but to the lap end pasting mechanism, which is controlled by the passing cans.

The machine as thus constructed has not only the advantages that the paste applying mechanism being operated only at intervals corresponding to the passage of the cans, economizes paste and avoids smearing and the production of an unsightly package on account of the use of an excessive amount of paste or cement, but has the further advantage that the paste or cement applying mechanism being in operation for a small fraction of the total period of operation of the machine, a considerable amount of power is saved.

The new machine has the further advantage that it may be used with but slight adjustment in applying both full length labels which extend entirely around the can, and panel labels which extend about a part only of the circumference of the can.

In this connection it is noted that in applying paste to the labels before they are picked up by the cans the paste must be rubbed over the surface of the label and there is a considerable tendency in this operation to displace the top labels from the pack on account of their tendency to adhere to the cement or paste applying device. This tendency has been overcome in the present instance by the provision of a presser foot which engages one end of the label, the applying means being drawn over the label toward the other end.

This presser foot, however, might have a tendency to either tear the labels when they are picked up by the cans or cause them to slip relatively to the surface of the can by

pulling them over the surface of the can displacing them from the position which they have taken in picking up, as described, and causing them to fail to stick or to be inaccurately located on the can.

To overcome this difficulty the machine of the present invention is provided with means for raising the presser foot to release each label in turn simultaneously with the picking up operation.

In the accompanying drawings I have illustrated a machine embodying the improvements of my invention in the preferred form.

15 In the drawings:

Figure 1 is a top plan view of the forward or receiving end of the machine into which the cans are fed.

20 Figure 2 is a top plan view of the central portion of the machine, certain upright portions being cut away and being shown in section.

25 Figure 3 is a plan of the rear or discharge end, the three figures comprising a complete plan of the machine.

Figure 4 is a side elevation of the front or receiving end of the machine.

30 Figure 5 is a corresponding view of the central portion of the machine, certain projecting portions near the observer being removed and sectioned.

35 Figure 6 is a side elevation of the discharge end of the machine, Figures 4, 5 and 6 comprising a complete side elevation of the machine.

Figure 7 is a fragmentary section on the line 7—7 of Figure 1.

40 Figure 8 is a section on the line 8—8 looking to the left in Figure 1.

45 Figure 9 is a section on the line 9—9 of Figure 1 showing the pick-up paste applying mechanism in detail, particularly the roller guide.

50 Figure 10 is an enlarged fragmentary view corresponding to Figure 4 and showing the intermittent gearing for actuating and pasting mechanisms for pick up.

Figure 11 is a view of the same mechanism taken from the left, as seen in Figure 10.

55 Figure 12 is a top plan view of the cement or paste pot holding the supply of cement to be applied to the pick up ends of the labels, the illustration including the roller by which the cement is supplied to the applying roller.

Figure 13 is a front elevation of the same.

Figure 14 is a section on the line 14—14 of Figure 13.

60 Figure 15 is an elevation of the label pack showing the presser foot and label curler in section on line 15—15 of Figure 2, the parts being in position for handling short or panel labels.

65 Figure 16 is a corresponding view showing the presser foot raised as by the passage

of a can, the parts being adjusted for use with long labels covering the full circumference of the can.

Figure 17 is a plan of a can with a full length label in position thereon.

70 Figure 18 is a plan of a can bearing a panel label.

Figure 19 is a section through the ways on the line 19—19 of Figure 3, showing a can fully labeled about to be discharged 75 from the machine.

Figure 20 is an elevation at right angles to Figures 15 and 16 showing a section of presser foot.

Fig. 21 is a side elevation of the lap end 80 pasting belt presser.

Figure 22 is a side elevation of the drive clutch for lap end pasting mechanism as viewed from the left of Figure 5.

Figure 23 is a section on the line 23—23 85 of Figure 22 looking in the direction indicated by arrows.

Figure 24 is a plan view of the drive clutch mechanism similar to that disclosed in Figure 2, but shown on an enlarged scale. 90

Referring to the drawings by numerals, each of which is used to indicate the same or similar parts in the different figures, the machine as shown comprises supports or legs 1 on which are mounted longitudinal side 95 bars or frames 2, 3. The machine also includes pulley drive 4 and idler pulley 5 at the opposite ends on which runs the can belt 6 contacting the cans from above and by means of which the cans are passed through 100 the machine rolling on the ways 7. The belt is driven from any suitable source, as an electric motor, not shown, which in the present form of the machine is mounted on the supporting frame near the floor. This 105 motor drives the diagonal shaft 8 in Figure 6 which operates the belt driving pulley 4 by way of suitable gearing contained in the gear case 9.

As already outlined the invention relates 110 particularly to the paste applying mechanism and the manner of actuating the same intermittently to correspond to the presentation of the cans.

In Figures 4, 10 and 11 I have illustrated 115 the primary intermittent drive for the paste applying means, the same consists of a shaft 11 mounted in suitable bearings 12 in the frame and extending across the machine. This shaft carries loosely mounted thereon 120 a sprocket 15 driven by a chain 16 from a sprocket 17 secured to the belt pulley 5. The sprocket 15 is provided with a projecting clutch member 18 on the right in Figure 11, the same having clutch teeth 19 125 which cooperate with clutch teeth 20 on a sliding clutch member 21, which is keyed to the shaft 11 by means of a key 22. A coil spring 24 encircling shaft 11 at the right of the sliding clutch member imparts to it 130

a tendency to move to the left into engagement with the clutch member 19 on the sprocket 15.

The clutch member 21 is controlled by a 5 sliding bolt 25 operated by an arm 27 secured to a shaft 28 having a bearing in the frame, as shown in Figure 4. The arm 27 is provided with a horizontal foot 29 through which the bolt is passed, the bolt 10 having secured thereto a collar 30 which rests on the arm, the bolt 25 being also passed through a bearing 31 on the frame and having a coil spring 33 encircling the bolt between the collar 30 and the bearing 15 31, engaging both said members and thrusting the bolt and collar downwardly.

The shaft 28 also carries secured thereto a rearwardly extending arm 34 in the form of a double U shaped member, see Figures 20 1, 4 and 7, which extends across the path of the cans, the arm 34 as it swings about the shaft 28 has a vertical motion, being in its upper position in the path of the cans as aforesaid. This refers particularly to 25 cross bar 36.

As each can passes along the ways, the cans being fed from the right to the left, Figures 1, 2, 3, 4, 5 and 6, it engages and depresses the arm 34, which is held in its 30 upper position by the spring 33, thereby rocking the shaft 28, as seen in Figure 4, in right handed rotation, raising the arm 27 with the foot 29 and the bolt 25.

The bolt 25 in its advanced or depressed 35 position engages a cam path or shoulder 37 on the sliding clutch member 21, which cam path as shown particularly in Figure 11 is inclined to the axis of the clutch member. In the position shown in Figure 11 the bolt 25 40 being advanced, engages the high point of the cam surface 37 holding the sliding clutch member 21 out of engagement with the clutch member 19 carried by the continuously rotating sprocket 15. When, however, 45 the tripping lever 34 is depressed by the passage of a can along the ways, the arm 27 being swung upwardly in right handed rotation withdraws, i. e., raises the bolt 25 and permits the clutch member 21 to move 50 to the left into engagement with the clutch member 19. Under these circumstances, the clutch members being in engagement, the shaft 11 is rotated, the bolt 25 is, however, immediately released by the passage of the 55 can over the arm 34, which arm is immediately raised, the bolt being simultaneously advanced or depressed by the action of the spring 33. As soon as the can has passed the arm 34 the latter is released and tends 60 to rise impelled by the tendency to left handed rotation about the shaft 28 imparted to the arm 29 by the spring 33. The bolt 25, however, encounters the peripheral surface 38 of the cam from which it is dropped 65 in due course by rotation of the cam bring-

ing the low point thereof, 39, opposite the bolt when the latter is engaged by the cam from the right hand side in Figure 11 after the manner of a follower, and containued rotation of the shaft 11 brings the high point 70 40 of the cam again in contact with the bolt causing the clutch to be released. In this way a single rotation is imparted to the intermittent actuating shaft 11 on the entrance of each can into the machine, and the adhesive handling or pasting mechanism, including both the pick-up and lap end pasting features, is actuated by and from this shaft as hereinafter described.

To provide for the efficient operation of 80 the device as controlled by the passage of the cans, the cans are so timed as admitted to prevent interference of one can with the other and particularly the passage of two cans so close together as to interfere with 85 the functioning of the intermittent gearing and the corresponding operation of both pasting mechanisms, the term pasting being used for convenience in connection with the application of glue, cement or paste.

The cans as they enter the machine are spaced or timed by means of a can gate 43, which, in the form of the invention shown, is placed at the forward end of the ways 7, see Figure 4, also Figures 7 and 8, and 95 at the delivery end of the feed chute 44. This gate 43 in the form of the invention shown is integral with a pivoted or trigger section 45 of the ways 7, consisting of two tracks 45' connected by cross braces 45'', which is pivotally mounted on a transverse shaft 46 beneath the ways to operate the gate. The gate 43 is shown as in the form of two uprights, one at the end of each track 45' of said way section 45. This can gate 100 43 operates in a transverse slot 47, on one side of which slot is the rear end 49 of the chute 44 and on the other the forward end of an inclined runway 48, down which the cans roll on to the ways 7. The forward portion of the trigger section 45 is depressed at 50 beneath the runway 48. The trigger section 45 of the ways, as shown, is also notched at 51 to provide for the operation of the arm 34 without interference of said arm with the operation of the trigger, the two being differently timed for certain parts of the said operation.

The rearward end 52 of the trigger section 45 of the ways 7 is sufficiently spaced 120 from the gate 43, i. e., the trigger section is of sufficient length to so time or space the cans as to permit the pasting mechanism to operate intermittently as already suggested without interference of one can with another and it prevents the presentation of a can to the label pack after the passage of the previous can before the mechanism is ready to receive it. The gate is held normally depressed by helical tension springs 130

53. There are two springs as shown in Figure 8, said springs being connected at their upper ends to the gate at 54, Figure 8, and at their lower ends to depending brackets 55 secured to a stationary portion of the frame, the connections being indicated by reference character 56, the normal position of the gate being as shown in Figures 4 and 7.
- 10 As each can is admitted to the machine from the chute 44, it passes over the gate 43 which is normally in depressed position and down the incline 48, see Figure 7, coming immediately in contact with the pivoted section 45 of the ways 7, which, when the gate is depressed, is inclined upwardly to the rear as shown in Figure 7. Simultaneously the can is engaged from above by the can belt 6 and moved forward independently of the momentum acquired by the inclines which it has just passed, and the swinging section 45 is by weight of the can thus rotated downward into horizontal position as shown in dotted lines in Figure 7.
- 15 This raises the gate into the path of the next can. The swinging or rearward end 52 of the trigger then rests on the frame, particularly the cross bar 57, which is stationary and as shown extends from the side bar 2 to the side bar 3 on the other side, resting on both members. The cans accumulate on the chute and as each can is released by the gate it moves quickly down the incline and contacting the member 45 closes the gate in time to stop the next can before it acquires headway.
- 20 To overcome the tendency of the cans on account of their momentum and other agencies, to hop over the gate when the latter is partly or fully raised, means has been provided in the nature of a can check 59 placed over or substantially over the gate and spaced above the floor of the chute 44 by slightly more than the diameter of a can.
- 25 This prevents the passage of the cans over the gate unless the latter is as low as or below the chute floor, i. e., in open or lowered position. This can check consists of a strap or bar which may be described as U shaped in cross section, the same having legs 60 secured by bolts 61 to the uprights 62 which carry the belt pulley 5. The can check moves up and down with the adjustment of the pulleys and the uprights 62, as will be easily understood, the upright being vertically slidable through bearing 63 and held by cap screw 64. Section 45 of the ways 7 is held in depressed or horizontal position by the can until the latter has passed the rearward end 52 of the swinging section and in this position the check or gate 43 is in a position in which it obstructs the passage of the cans, see the dotted line position of the same in Figure 7. As each can passes the trigger 45, releasing the same by moving off
- 30 of the end 52 of the swinging section of the ways, the latter swings upwardly to the normal position in which it is illustrated in Figures 4 and 7. In this position of the swinging section the gate being lowered to the full line position, Figures 4 and 7, the next can is admitted to the machine moving forward immediately on the lowering of the gate from the path of the cans. By this operation, i. e., the release of one can permitting it to pass the gate when and not unless the next preceding can has passed from the end of section 45, the cans are timed and spaced by a distance exactly equal to the length of the member 45 from and including the rearward or swinging end 52 to the gate 44.
- 35 The pack of labels 58 is supported on any suitable type of label table 65, see Figure 9, and the cement or pick-up adhesive is applied to the forward end of each label as it comes to the top of the pack in turn by means of a pick-up paste roller 66. This roller is fed or supplied with paste by means of a paste pot roller 67 which rotates in the pick-up paste pot or cement pot 68, see Figures 12, 13 and 14. The pick-up paste roller 66 is applied to the paste pot roller 67 and to the top label of the pack 58 alternately by the following mechanism.
- 40 The machine is provided with a depending bracket 69 in the lower end of which is seated a stud 71 on which an arm 70 is pivotally mounted to swing in a fore and aft vertical plane. The arm 70 extends upward from the stud 71 to the level of the side bars 2, 3 and carries pivotally connected to the upper end of the arm at 72 a connecting rod 73 which is offset at 74 upwardly to the plane of the ways, from which point it extends rearwardly to the roller 66. Figure 9, where it is offset downwardly at 75, being provided at its rearmost lower end with a bearing for the roller shaft 76. The arms 70 and connecting rod 73 are duplicated on the opposite sides of the machine forming actuating means and a support for both ends of the roller. The upright arm 70, in the machine shown the one of said arms on the far side of the machine, see Figure 4, is actuated by means of a connecting rod 78 pivotally connected at one end to a central point on the upright arm 70 at 79 and at the other end by means of a crank pin 80 to the swinging end of an arm 81 on the shaft 11, already described as carrying the clutch 18 and intermittently operated thereby. The operation of the clutch by the cam 37 being so timed and controlled by the automatic clutch controlling cam 37, described, as to impart to the roller a single longitudinal reciprocation, meaning a complete forward and backward stroke, for each engagement of the clutch.
- 45 The roller 66 is guided into contact with the labels and the paste pot roller 67 by 130

means of a cam path and switch, Figure 9, engaging the shaft 76. The cam consists of a plate 83 secured to each side frame member and having a cam path opening 84, the 5 outline of which conforms roughly on the upper side to the path of the upper side of the shaft on the rearward motion of the roller and as to the lower side to the path of the bottom of the shaft on the forward 10 stroke of the roller. The roller shaft 76 is guided into the upper or forward path by means of an automatic switch 85 which is pivotally mounted intermediate of the cam opening near the rearward end of the latter. 15 As shown, the pivot is about one-quarter of the length of the opening from the forward end, the pivot being indicated by reference character 86. The switch, as shown, is bent or curved intermediately at 87 so that its upper 20 surface conforms to the upward and rearward path of the roller shaft. The lower forward end of the switch is preferably pointed at 88 and the cam opening 84 is provided with a pocket 89 on the lower 25 rearward side of the opening into which the point of the switch drops by gravity when the roller shaft is in the forward lower extremity of the cam opening which occurs when the pasting roller 66 is in contact with 30 the paste pot roller 67. A spring 86' may assist in throwing the switch, see Figure 5.

In this position of the parts the rearward thrust imparted to the pivoted roller arm 73 by the swinging upright arm 70 causes the 35 shaft 76 of the roller 66 to move upwardly and rearwardly along the upper inclined surface 90 of the switch. As the roller shaft encounters the horizontal portion of the switch beyond the bend or curve 87 the roller 40 moves rearwardly in a horizontal direction above the labels and as the shaft passes the pivot 86 which may be seated in a second plate 92 secured to the back of the first plate, see Figure 1, the switch tips in left handed 45 rotation about the pivot and the shaft moves down the incline into contact with the rearward end portion of the opening 84 at 93. At this point the motion of the crank pin 50 and of the swinging arm 70 is reversed 55 as the crank pin passes the rearward dead point and the roller 66 moves toward the forward end of the machine, i. e., to the right in Figure 9, and the shaft 76 moves forwardly down the incline 93 bringing the roller 66 into contact with the top label. As 60 the roller moves toward the front end of the machine this single forward stroke of the roller, corresponding to the horizontal path 65 94, applies the pick-up cement to the pick-up or forward end of the top label. The rise 95 carries the roller over the gage 96, and end of label.

The paste pot roller 67 is driven through toothed sprocket 115 on the stud 120, which 65 sprocket is engaged by the chain 16 which

drives the sprocket 15 on the shaft 11. This sprocket 115 carries a toothed gear 117 which meshes with a gear 121 on the shaft 116 carrying roller 67. This shaft carries near the paste pot a gear 119. The pick-up 70 pasting roller 66 is provided on the end of its shaft 76 with a gear 118 which in the position of the pasting roller shown in Figure 9 in which it contacts the paste pot roller 67, meshes with the gear 119. This 75 provides for the uniform spreading of the paste on the roller 66 when it is in contact with the paste pot roller.

To prevent displacement of the top labels by the action of the roller 66, pressure is applied to the top of the pack by means of a presser foot 97, see Figures 15, 16 and 20. This presser foot is in the form of a bar extending across the top of the label pack at right angles to the direction of the feed and 80 the length of the machine. In the form shown the pressure thus applied to the labels is due to the weight of the parts, though the invention is not limited to this detail. As the picking up of the labels is dependent on 85 the instantaneous adhesion of the forward ends of the labels to the cans as they pass, the grip of the presser foot if continuously applied might be sufficient to displace the labels or even prevent them from being picked up. 90 To avoid possible interference with the operation of the machine in this way, means is provided for raising the presser foot to release each label from the presser foot as it is picked up. To this end a connecting rod 100 98 is pivotally connected to the presser foot or bar at each end of the latter and at each side of the machine. The presser foot bar is provided at each end with an upright or cross head 99 secured thereto. This cross 105 head runs in guides 104 on the frame, see Figures 2 and 15, and to these cross heads the connecting rods 98 are pivotally connected as aforesaid.

The connecting rods 98 are connected at 110 their upper ends, see Figure 5, to a swinging lever 100 pivotally mounted at 101 at each side on the machine frame and extending forwardly at each side of the upper portion of the path of the cans. The swinging arms 100 carry the can feeler roller 102 extending across the path of the cans, to engage the upper portion of the latter. This is mounted at each end in one of the feeler arms 100 and the connecting rods 98 are pivotally connected to the arms at 103 forwardly of the roller. Arms 100 also rest on belt presser roller 108.

The rear ends or lap ends of the labels are 115 paste coated by means of lap end pasting belt 105 shown in section in Figures 15 and 16 and to be further described. It is apparent from the description that after each can has picked up the front end of the top label and rolled backward over the lap end past- 120

125
130

ing belt which covers the rear ends of the labels, it will contact the feelers 102 and 108 and raise the presser foot releasing the rear or lap end of the label just as tension is applied to it by the can. To prevent scraping of the adhesive from the rear or lap ends of the labels as they are drawn from under the presser bar the latter is provided with a succession of notches 106 spaced along its lower 10 surface as shown in Figure 20. By this arrangement the paste on the portions of the surface of the lap ends of the labels which register with the notches is undisturbed.

The machine is provided with any usual 15 or suitable curler bar 107. With the full length labels which extend entirely around the can lapping over at the outer or rear end of the label the normal operation of the curler bar as well understood in the art is 20 entirely satisfactory, but the present machine is intended for use with short or panel labels as well as with the full length labels. The panel panel labels cover a half or a third of the circumference of the can. Such 25 labels are more easily dislocated or entirely removed from the can by the action of the curler bar. To provide for the use of short or panel labels and to obviate the danger that the labels may be dislocated or removed 30 from the cans after picking up, means is provided in the present machine in connection with the presser foot whereby the grip of the curler bar may be released to any desired degree at the moment of the final withdrawing of the rear end of the label which 35 corresponds to the lap end in the long labels, the degree to which the grip is released at this time being preferably adjustable.

The means for releasing the grip of the 40 curler bar comprises depending brackets 109, one at each end of the presser foot and secured thereto by any suitable means as shown. Each of said brackets carries a thrust pin 110, which is preferably made 45 vertically adjustable in said bracket. In the form shown the pin 110 is threaded and the bracket has a horizontal foot 111 with which the pin is engaged, being passed through a suitable vertical aperture 112 50 therein, which aperture is suitably threaded for engagement of the threads on the pin. This threaded pin is shown as provided with a suitable knurled head 114 below the bracket.

55 When the short labels are used the pin is turned up into engagement with the curler bar as shown in Figure 15, the length of the pin being adjusted to give the desired relaxation of the grip of the curler bar, which 60 results in the necessary amount of curling without applying sufficient tension to the label to remove or dislocate it. Figure 16 shows the adjusting pin 110 withdrawn so as to provide for the use of the full length

labels. With the adjustment shown in Figure 16 the raising of the presser foot does not change or release the grip of the curler bar, the presser being shown in this connection in raised position. The adjustment in Figure 15 provides for raising of the curler bar 70 simultaneously with the raising of the presser foot. This raising of the curler bar may be deferred and reduced by lowering the pin. This is the extreme adjustment and in operation should be such as to give the 75 desired timing and pressure and hence the right degree of curling of the label as it is withdrawn.

The paste pot roller 67 as shown in Figures 12, 13 and 14 is grooved circumferentially at 123, the grooves being spaced apart in the direction of the length of the roller. As shown, the spacing is slightly greater than the width of the grooves. The grooves provide for the retention and distribution 80 of the paste and to equalize the paste a scraper or gauge 124 is supported in the paste pot adjacent the roller. This scraper or gauge 124 is secured by means of screws 125 to a scraper or gauge supporting plate 85 127 which is adjustably mounted on an upright 128 in the paste pot. The gauge supporting plate 127 is secured to the upright in the form of the invention shown by means of screws 129 seated in the upright 128 and engaging slots 130 in the supporting plate 127. To provide for access to the screws 129 and to permit the same to engage the top of the supporting plate 127 the scraper or gauge 124 90 is apertured at 131 around the screw and slot. The arrangement of the parts described provides, when the screws 129 are loosened, a free adjustment of the gauge carrier or supporting plate 127 toward and from the paste pot roller 67. For the purposes of such adjustment the gauge supporting plate is moved by screws 133 having a threaded engagement with suitable bosses 134 located in the side of the paste pot and apertured and threaded for this purpose. The screws 133 95 have a swivel connection at 135 with an upright portion 136 of the plate 127.

Both pasting mechanisms are dependent 100 on the admission of cans to the machine and are operated once for each can so admitted, so that whenever the supply of cans is discontinued the paste coating operation is also discontinued and the top label remains dry 105 ready to receive a fresh supply of paste whenever the machine is started.

The mechanism for coating the lap end of 110 each label with adhesive is driven from longitudinal shaft 145 which is in turn driven, see Figures 1 and 4, by bevel gears 143 and 144, 115 the latter being connected to a sprocket 140, the bevel gear 143 and the sprocket being connected to rotate together and mounted 120 on the same transverse stud or shaft 141.

The sprocket 140 is driven by the previously mentioned chain 16 which runs constantly and drives shaft 11.

The shaft 145 carries a toothed clutch member 146 see Figures 2, 5, 22, 23 and 24 which, in the form of the invention shown, is keyed thereto by means of slot 147 to rotate therewith. The clutch member 146 is provided with clutch teeth 148 projecting to the right or forwardly in Figures 2 and 24. This clutch member is held in position on the shaft 145 by a rigid arm 149 on a bracket 150 secured to the side frame 2. This arm 149, as shown, carries an arcuate wiper 151 which enters a groove or track 152 in the clutch member between flanges 153 thereon. The shaft 145 also carries a freely rotating lap end paste belt pulley sleeve 155 on which is mounted a clutch member 156 having teeth 157 which cooperate with the teeth 148 of the first mentioned clutch member. This clutch member 156 is keyed to the sleeve 155 by means of a key 158 to rotate therewith and slide in the direction of the axis of the shaft and sleeve. The sleeve 155 also carries secured thereto the lap end paste belt drive pulley 159 and a helical spring 160 is wrapped around the sleeve between the said pulley 159 and the clutch member 156 bearing against both said members and tending to thrust the clutch member 156 into engagement with the clutch member 146. The clutch member 156 is also provided with a cam member 161 with a radial cam surface 162 having a high point 163, which, in the position of the machine shown in Figures 2 and 24, is engaged by a pin 164 mounted to slide in a bearing 165 mounted on a stationary part of the machine. This pin is provided with a nut 166 or any suitable shoulder at its upper end and is engaged beneath the shoulder or nut by an upright forked lever 167 extending upwardly from shaft 168 mounted in suitable bearings 169 in the bracket 150. The pin 164 is normally advanced by the action of a tension spring 170, see Figure 2, connected to the fork 167 and to the bearing 165 and the fork 167 engages a shallow groove 171 in the pin or bolt, making the latter move with the fork. The shaft 168 also carries an arm 174 inclined slightly downwardly from the horizontal as it leaves the shaft which projects into the path of the cans just beyond the lap end pasting belt 105. The cans are supported in this position by a plate 176 which rests on the ways 7 and leads the cans up to the pads 200. This plate 176 is notched at 179 to admit the end of the arm 174 and the arm is held in raised position slightly above the plate and in the path of the cans by the tension of the spring 170 which applies a constant tension to the fork 167 tending to swing it toward the observer in Figure 2.

As each can advances over the plate 176

after passing the lap end pasting belt and approaches the pads, it passes over the end of the lever arm 174 depressing the same and withdrawing the bolt 164 from contact with the cam surface 162, particularly the high point of the same, 163.

The withdrawal of the bolt 164 permits the clutch member 156 to move to the left in Figures 2 and 24 in response to the pressure of the spring 160 causing the teeth 157 thereon to come into engagement with the clutch teeth 148 of the clutch member 146 so that the sleeve 155 is locked to the shaft 145 which, as aforesaid, is rotated continuously driven by and from chain 16 through sprocket 140 and bevel gears 143 and 144. As soon as the can passes, the pin 164 is advanced by the spring 170 and contacts the outer surface 162 of the cam. When the low point of the cam comes opposite the pin the latter advances to the normal position, Figures 2 and 24, engaging the cam surface and further rotation brings the high point 163 into engagement with the pin releasing the clutch. Stop pin 173 seated in the member 156 engages the pin 164 in the out or stationary position of the clutch preventing the parts from being further rotated by the momentum thereof which would carry the high point of the cam by the follower pin, and would cause the clutch to re-engage and continue the parts in rotation. The stop and cam control limit each operation of the sleeve 155 and paste belt pulley 159 to a single revolution.

More briefly stated the mechanism just described is a single revolution clutch controlled by the horizontally sliding pin 164, the clutch being engaged by the action of spring 160 when the pin is withdrawn by the passage of the can over the arm 174. As soon as the pin or bolt 164 is released after the passage of the can, the pin or bolt returns to engagement with the cam member and rotation of the cam member to high point 163 disengages the clutch, rotation of which is stopped by contact of the pin 173 on the clutch with the horizontal sliding pin or bolt 164. The operation of this clutch is substantially the same as that of the clutch 18 illustrated in detail in Figures 10 and 11.

The mechanism first described provides for the intermittent operation of the pick-up paste coating roller imparting a single stroke to the roller on the admission of each can to the machine whereby the roller is moved to the rear, brought in contact with the label and moved forwardly in contact with the label, coating a portion near the forward or pick-up end of the label with adhesive. The mechanism just described controlling the lap end paste coating belt is a second intermittently operating mechanism whereby the belt is moved one step each time a can passes from the label table.

The illustration, Figure 2, includes paste pot roller 182 whereby the paste is picked up from the pot and applied to the lap end pasting belt 105. This roller is mounted on a shaft 183 to which is secured a sprocket 184 driven by a chain 185 from a sprocket 186 secured to the lap end paste belt pulley sleeve 155, carried by the lap end pasting shaft 145. The construction and operation 10 of the lap end paste coating mechanism, so far as this detail is concerned and other details not relating to the intermittent drive, is similar to generally known prior art structures understood by those skilled in the construction and operation of such machines.

A feature of interest in connection with the operation of the present device is the belt presser 190, Figures 21 and 2. The same consists of two levers, one at each side 20 of the ways, the pivots 191 being carried by suitable brackets 192. These belt pressers are well known. They rest on and are supported by the belt projecting slightly above the can supporting surface of the ways. As 25 each can passes they are engaged from above by the can and pressed downward against the belt which is in turn pressed against the lap end of the label. As each can passes from the label table, as aforesaid, 30 the lap end paste belt operating mechanism is tripped and operated imparting to the lap end paste belt pulley 159 a single rotation advancing the paste belt a corresponding distance bringing a newly paste coated 35 portion of the belt over the top label on the table.

As the cans or packages, each bearing a newly pasted label, pass from the lap end pasting mechanism rolling across the plate 40 176, they encounter the pads 200 and 201 which are spaced and located corresponding to the location and spacing of the ends of the labels. These pads are preferably of sponge rubber or other extremely resilient 45 material. The pads serve to flatten the labels against the surface of each can, particularly at the ends where they are coated with adhesive, the pads being so spaced where panel labels are used as to engage the pick up and 50 lap end portions of the label respectively, so that as it passes, the can is supported on and between the pads applying tension to the labels from the center toward the ends. The pads are movable and adjustable in the 55 direction of the length of the ways, as hereinafter described, and where a full length label is used extending entirely around the can, the pads may be placed in contact with each other or a single pad may be used. The 60 adjustment provides for variation in length of the panel labels, making it possible under all circumstances where labels of different lengths are used to so place the pads as to cause them to register with the respective 65 end portions. Between the pads 201 and

200, and on both sides of them, the cans are suitably supported. As shown, the support comprises blocks of rubber 203, thinner than the pads so that the top surface of the pads is higher than the adjacent supporting surface and the pads project into the path of the cans or packages. These blocks may be of any suitable material either similar to the pads or of less resilience. In the form of the invention shown the pads 200 and 201 and 70 the intermediate and end blocks 203 are supported on angle irons 204 which are practically in alignment with the ways. The blocks are preferably cut to fit in the angles and may be arranged thereon to give the 75 desired spacing, the intermediate block 203 and the end blocks 205 being removed to provide for the free spacing of the pads 201 and 202 after which the area, if any, between the pads and at the ends of the pads is 80 filled in by suitable blocks 203. In addition to the normal function of flattening the ends of the labels against the cans, the resilient pads also serve to enter the irregularities and the holes in the cans, which 85 result from various causes. These are sometimes due to blows or bumps which the cans receive and to the existence of a vacuum in the cans as a result of the canning process, which permits the cans to collapse to 90 a greater or less degree in response to atmospheric pressure. By this means the labels are brought into close contact and caused to adhere closely even when the surface is 95 irregular and depressed, as described. 100

The cans are spaced by the gate 43 a distance a little greater than the length of the labels and as each can is admitted it trips the pick-up paste or cement coating mechanism which imparts a single stroke to the roller 66, which is normally in contact with the paste pot roller 67, passing it upward, backward, dropping it on the top label and bringing it forward in contact with the forward end of the label. As the same can 105 passes backward through the machine over the top label on the table it encounters the belt presser 190 over the lap end paste coating belt, a newly coated portion of which 110 has just been advanced by the action of the previous can, as aforesaid, pressing said newly coated portion of the belt downward against the top label on the pack. The can passes out of contact with the belt presser 115 before the lap end of the label is withdrawn from beneath the belt the presser bar and the label curler, the grip of which latter two members is released by the action of the lifting mechanism already described. The 120 labels are thus left clean, uncoated and ready to receive the paste on the admission of a can and the coating mechanism remains inoperative whenever the feeding of cans is interrupted for a short or long period so 125 that drying of paste on the top label and 130

accumulation of an excess of paste due to intermittent feeding is avoided, as is also loss of power due to continued operation of the mechanism during interruptions of the 5 can feed, the machine being thus rendered wholly automatic.

The paste coating mechanism being completely controlled by the cans, supervision of the machine in operation is almost entirely dispensed with, the greatest possible 10 economy of power used in the operation of the paste coating appliances is effected, and the machine is made available for use where it previously could not be used economically 15 on account of the intermittent supply of cans or packages and the necessity for supervision, and the economy of operation under the circumstances is greatly increased.

I have thus described specifically and in 20 detail a single embodiment of my invention in order that the nature and operation of the same may be clearly understood, however, the specific terms herein are used in a descriptive rather than in a limiting sense, 25 the scope of the invention being defined in the claims.

What I claim and desire to secure by Letters Patent is:

1. In a machine for labeling cylindrical 30 packages, ways, means for rolling the packages along the ways, means for supporting a supply of labels adjacent the ways so that the packages roll over the top label as they pass, a paste pot and a paste roller 35 therein and means for rotating this roller independently of the motion of the packages and means contacting said roller for applying adhesive to the forward end of each label as it comes to the top of the pack and tripping means in the path of the packages at 40 the front end of the machine controlling said adhesive applying means to operate the same as each package is introduced into the machine.

2. In a machine for labeling cylindrical 45 packages, ways, means for rolling the packages along the ways, means for supporting a supply of labels adjacent the ways so that the packages roll over the top label as they pass, a paste pot and a paste roller 50 therein and means for rotating this roller independently of the motion of the packages and means contacting said roller for applying adhesive to the forward end of each label as it comes to the top of the pack, tripping means in the path of the packages at the front end of the machine controlling 55 said adhesive applying means to operate the same as each package is introduced into the machine and means for spacing the packages to provide a sufficient interval between the packages to provide for the operation of the adhesive applying mechanism.

3. In a machine for labeling cylindrical 60 packages, ways, means for rolling the pack-

ages along the ways, means for supporting a supply of labels adjacent the ways so that the packages roll over the top label as they pass, means for applying adhesive to the forward end of each label as it comes to 70 the top of the pack, tripping means in the path of the packages at the front end of the machine controlling said adhesive applying means to operate the same as each package is introduced into the machine, means 75 for spacing the packages to provide a sufficient interval between the packages to provide for the operation of the adhesive applying mechanism, said latter means comprising a member pivotally mounted at the front 80 of the machine and having an upright portion comprising a gate moving transversely to the path of the packages into and out of the path of the packages, and a longitudinal arm extending rearwardly of the pivot along 85 the path of the packages and in the open position of the gate projecting upwardly from the path of the packages to be engaged and depressed by each package as it passes, the movement of the arm serving to raise 90 the gate into the path of the next package.

4. In a machine for labeling cylindrical packages having ways, means for rolling the packages along the ways, means for supporting the labels adjacent the path of the packages so that the top label is engaged by each package as it passes, tripping means at the front of the machine in the path of the packages to be tripped by each package as it enters, means controlled by said tripping 95 means for applying paste to the front portion of the top label in the pack, tripping means in the path of the packages beyond the label support and means controlled by said second tripping means for presenting a supply of paste to the lap end of each label, said latter means comprising a paste belt extending across the label pack and across the path of the packages whereby the next package as it passes depresses the belt into contact with the label, applying the adhesive to the same.

5. In a machine for labeling cylindrical packages having ways for the packages with label presenting means in operative relation 115 with the ways, label pasting means and means controlling the same extending into the path of the packages to be tripped thereby, a gate for spacing the packages comprising a member pivoted at the front end of the machine and having an upright portion spaced forwardly of the pivot and a rearwardly extending portion which in the normal or open position of the gate projects into the path of the packages to be engaged thereby whereby each package as it passes the gate engages the rearwardly projecting portion closing the gate holding it in closed position until the package has passed the rearwardly projecting portion when the 120 125 130

gate is released and permitted to return to normal open position admitting the next package and spacing the packages.

6. In a machine for labeling cylindrical packages having ways for packages, means for maintaining a supply of labels adjacent the ways whereby each package as it passes moves in rolling contact along the top label of the pack, means for coating the forward end of the top label of the pack with adhesive comprising a roller, means for supplying adhesive to the roller, means for moving said roller upward and backward, downward and forward, the latter motion being in contact with the top label at the forward end thereof and returning the same into contact with the paste supplying means, and means at the forward end of the machine in the path of the packages for tripping said mechanism at each package passes.

7. In a machine for labeling cylindrical packages having ways for the packages, means for maintaining a supply of labels adjacent the ways whereby each package as it passes moves in rolling contact along the top label of the pack, means for coating the forward end of the top label of the pack with adhesive comprising a roller, means for supplying adhesive to the roller, means for moving said roller upward and backward, downward and forward, the latter motion being in contact with the top label at the forward end thereof and returning the same into contact with the paste supplying means, said means including an intermittently rotating member, means for converting the motion of said member into reciprocating motion and imparting the same to the roller, and means for guiding the roller along the path described.

8. In a machine for labeling cylindrical packages having ways for the packages, means for maintaining a supply of labels adjacent the ways whereby each package as it passes moves in rolling contact along the outside label of the pack, means for coating the forward end of the outside label of the pack with adhesive comprising a roller, means for supplying adhesive to the roller, means for guiding said roller into contact with the outside label and into contact with the paste supplying means, an intermittently rotating member, means for converting the motion of said member into reciprocating motion and imparting the same to the roller, means in the path of the packages for tripping said mechanism as each package passes, and a gate for spacing the packages.

9. In a machine for labeling cylindrical packages having ways for the packages, means for maintaining a supply of labels adjacent the ways whereby each package as it passes moves in rolling contact along the outside label of the pack, means for coating the outside label of the pack with adhesive,

said means including an intermittently rotating member, means for converting the motion of said member into reciprocating motion and imparting the same to the applying means, and means for guiding said means into contact with the label, and means at the forward end of the machine in the path of the packages for tripping said mechanism as each package passes.

10. In a machine for labeling cylindrical packages having ways for the packages, means for maintaining a supply of labels adjacent the ways whereby each package as it passes moves in rolling contact along the outside label of the pack, means for coating the forward end of the outside label of the pack with adhesive, said means including an intermittently rotating member, means for converting the motion of said member into reciprocating motion and imparting the same to the applying means, and means for guiding said means into contact with the label, and means at the forward end of the machine in the path of the packages for tripping said mechanism as each package passes, said tripping means comprising a rock shaft, an arm projecting into the path of the packages at the front end of the machine, a sliding bolt and means on the rock shaft for actuating the sliding bolt and a clutch controlled by said sliding bolt.

11. In a machine for labeling cylindrical packages, ways for the packages, means for maintaining a pack of labels with the outside label of the pack in contact with the packages as they pass along the ways, means for coating the forward end of each outside label with adhesive comprising a roller, means for supplying adhesive to the roller, means for reciprocating the roller in the direction of the ways, including a continuously rotating shaft and means for driving the same, a clutch member secured to the shaft, a second clutch member rotating and sliding on the shaft and having a cam member with high and low points spaced in the direction of the axis of the shaft, a sliding bolt controlling said clutch member and adapted to be engaged laterally by said cam surface, the bolt being located and spaced so as to throw the clutch member out of engagement when in contact with the high point of the cam, the second clutch member having means tending to maintain it in engagement with the other clutch member, means transforming the rotary motion of the second clutch member to reciprocating motion and means for communicating said reciprocating motion to the pasting roller, means for supplying paste and means for guiding said roller into contact with said paste supplying means and then into contact with the forward end of the outside label.

12. In a machine for labeling cylindrical

packages, ways for the packages, means for supporting a pack of labels adjacent the ways whereby the packages pass along the outside label in rolling contact, means for applying adhesive with a drawing action to each outside label of the pack in succession whereby the packages are caused each to pick up the outside label of the pack as it passes, a presser member engaging the labels to prevent displacement during the application of the adhesive and means operated by each package as it passes for raising the presser member at the end of the picking up operation to release the label from the grip of the presser member.

13. In a machine for labeling cylindrical packages, ways along which the packages are rolled, means for supporting a pack of labels adjacent the ways whereby the packages pass along the outside label in rolling contact, means for applying adhesive with a drawing action to each outside label of the pack in succession whereby the packages are caused each to pick up the outside label of the pack as it passes, a presser member and a label curler engaging the rear end of the outside labels and means for raising both said members at the end of the picking up operation to release the label and prevent displacement of the same from the desired position on the package.

14. In a machine for labeling cylindrical packages, ways along which the packages are rolled, means for supporting a pack of labels adjacent the ways whereby the packages pass along the outside label in rolling contact, means for applying adhesive with a drawing action to each outside label of the pack in succession whereby the packages are caused each to pick up the outside label of the pack as it passes, a presser member engaging the labels near the rear end to prevent displacement during the paste coating operation, and means for raising the presser member to release the labels comprising a contacting member in the path of the packages as they complete the picking up operation, and means mounted to move in a vertical direction and operated by said contacting member, and connections to the presser member to raise the latter as each package passes the contact member.

15. In a machine for labeling cylindrical packages, ways along which the packages are rolled, means for supporting a pack of labels adjacent the ways, whereby the packages pass along the outside label in rolling contact, means for applying adhesive with a drawing action to each outside label of the pack in succession whereby the packages are caused each to pick up the outside label of the pack as it passes, a presser member engaging the labels near the rear end to prevent displacement during the paste coating operation, and means for raising the presser

member to release the labels comprising a contacting member in the path of the packages as they complete the picking up operation, and a member mounted to move in a vertical direction and operated by said contacting member, and means connecting said member to the presser member to raise the latter as each package passes the contact member, a curler bar and means connecting the same to the presser member to move therewith as the latter is raised.

16. In a machine for labeling cylindrical packages, ways along which the packages are rolled, means for supporting a pack of labels adjacent the ways whereby the packages pass along the outside label in rolling contact, means for applying adhesive with a drawing action to each outside label of the pack in succession whereby the packages are caused each to pick up the outside label of the pack as it passes, a presser member engaging the labels near the rear end to prevent displacement during the paste coating operation, and means for raising the presser member to release the labels comprising a contacting member in the path of the packages as they complete the picking up operation, and connections to the presser member to raise the latter as each package passes the contact member, a curler bar and adjustable means connecting the same to the presser member to move therewith as the latter is raised.

17. In a machine for labeling cylindrical packages, ways along which the packages are rolled, means for maintaining a pack of labels adjacent the path of the packages, causing the package to pass in rolling contact along the outside label, means for applying adhesive to the forward end of each top label in turn, comprising a roller, a continuously rotating shaft, a clutch, rotatable means connected to one side of said clutch, the other side of said clutch being connected to the shaft, means in the path of the package for operating the clutch as each package is admitted, means connecting the said rotatable means to the roller to reciprocate the same, means for supplying paste to the roller, and means for guiding the roller into contact with the paste supplying means and the label in turn.

18. In a machine for labeling cylindrical packages, ways along which the packages are rolled, means for maintaining a pack of labels adjacent the path of the packages, causing the packages to pass in rolling contact along the outside label, means for applying adhesive to the forward end of each outside label in turn, said means comprising a distributing roller and means for applying same to each label and to the paste supplying means in turn and means for supplying paste to said roller, said paste supplying means comprising a roller, means

for rotating the same, a toothed gear connected to said roller, a toothed gear on the paste distributing roller, the latter gear being brought in mesh with the gear on the 5 paste supplying roller when the distributing roller is in contact with the supplying roller to rotate the distributing roller and distribute the paste thereon.

19. In a machine for labeling cylindrical packages having ways along which the packages are rolled, means for supporting a pack of labels adjacent the ways so that the packages pass in rolling contact with the outside label of the pack, a lap end 10 paste belt running across the label pack transversely to the direction of the ways, means for supplying adhesive to the belt, a drive pulley for the belt, power operated means for rotating the pulley intermittently 15 to present a newly coated portion of the belt to the labels, and means for controlling said motion of the belt comprising a trigger member in the path of the packages.

20. In a machine for labeling cylindrical packages having ways along which the packages are rolled, means for supporting a pack of labels adjacent the ways so that the packages pass in rolling contact with the outside label of the pack, a lap end 25 paste belt running across the label pack transversely to the direction of the ways, means for supplying adhesive to the belt, a drive pulley for the belt, means for moving the same intermittently to present a 30 newly coated portion of the belt to the labels, comprising a rotating shaft, a clutch member connected to the pulley, means tending to maintain the clutch members normally in engagement thrusting one clutch member toward the other, means for controlling 35 said moving clutch member comprising tripping means in the path of the packages beyond the label pack in the direction of the feed whereby the clutch is engaged after each package passes the label pack and disengaged after a brief period of operation.

21. In a machine for labeling cylindrical packages having ways along which the packages are rolled, means for supporting a pack of labels adjacent the ways so that the packages pass in rolling contact with the outside label of the pack, a lap end paste belt running across the label pack transversely to the 55 direction of the ways, means for supplying adhesive to the belt, a drive pulley for the belt and means for moving the same intermittently to present a newly coated portion of the belt to the labels, comprising a rotating shaft, a clutch member on said 60 rotating shaft, a cooperating clutch member connected to the pulley, means tending to maintain the clutch members in engagement thrusting one clutch member toward the other, means for controlling 65 said moving clutch member comprising

ing clutch member comprising tripping means in the path of the packages beyond the label pack in the direction of the feed whereby the clutch is engaged after each package passes the label pack and disengaged after a brief period of operation, 70 belt pressing means in the path of the packages to depress the belt into contact with the label and means for timing the packages to avoid contact of the packages with the belt pressing means while the belt is in motion.

22. In a machine for labeling cylindrical packages having ways along which the packages are rolled, means for supporting a pack of labels adjacent the ways so that the packages pass in rolling contact with the top label of the pack, a lap end paste belt running across the label pack transversely to the direction of the ways, means for supplying adhesive to the belt, a drive pulley for the belt and means for moving the same intermittently to present a newly coated portion of the belt to the labels, comprising a rotating shaft, a clutch member on said rotating 90 shaft, a cooperating clutch member connected to the pulley, means tending to maintain the clutch members in engagement thrusting one clutch member toward the other, means for controlling said sliding clutch member comprising a bolt holding the moving clutch member out of engagement, a cam rotating with the clutch member having a high point which contacts the bolt to hold the clutch out of engagement, means tending to advance 95 the bolt and means in the path of the packages beyond the label table for withdrawing the bolt as each package passes, the cam having a low point which permits the bolt to advance into engagement with the cam 100 surface, continued rotation of the cam bringing the high point in contact with the bolt serving to disengage the clutch.

23. In a machine for labeling cylindrical packages having ways along which the packages are rolled, means for supporting a pack of labels adjacent the ways so that the packages pass in rolling contact with the outside label of the pack, a lap end paste belt running across the label pack transversely to the 115 direction of the ways, means for supplying adhesive to the belt, each package as it passes rolling over the belt and pressing the coated portion on the label it is picking up, and power operated means controlled by the 120 package as it leaves the label pack for moving said belt intermittently.

24. In a machine for labeling cylindrical packages having ways along which the packages are rolled, means for supporting a pack of labels adjacent the ways so that the packages pass in rolling contact with the outside label of the pack, a belt extending transversely to the direction of the ways, means for supplying adhesive to the belt, a drive 130

- 5 pulley for the belt and means for moving the same intermittently to present a newly coated portion of the belt to the labels, comprising a rotating shaft, a clutch member on said rotating shaft, a cooperating clutch member connected to the pulley, means tending to maintain the clutch members normally in engagement thrusting one clutch member toward the other, means for controlling 10 said clutch member comprising a bolt holding the moving clutch member out of engagement, a cam rotating with the clutch member having a high point which contacts the bolt to hold the clutch out of engagement, means tending to advance the bolt and means in the path of the packages beyond the label table for withdrawing the bolt as each package passes, the cam having a low point which permits the bolt to advance into engagement with the cam surface, continued rotation of the cam bringing the high point in contact with the bolt serving to disengage the clutch, and means rotating with the clutch to contact the bolt in the released position of the clutch preventing further rotation of the parts until the bolt is withdrawn.
- 15 25. In a machine for labeling cylindrical packages having ways, means for supporting a label pack adjacent the ways so that the packages pass in rolling contact with the top label of the pack, means for applying pick-up adhesive to the forward end of the top label, means in the path of the packages at the front end of the machine for controlling said means, means for applying adhesive to the lap end of the outside label of the pack and means beyond the label pack tripping said means.

26. In a machine for labeling cylindrical packages having ways, means for supporting a label pack adjacent the ways so that the packages pass in rolling contact with the top label of the pack, means for applying pick-up adhesive causing the package to pick up the top label, means in the path of the packages at the front end of the machine for controlling said means, means for applying adhesive to the lap end of the top label of the pack and means beyond the label pack tripping said means, and means at the front end of the machine for spacing the packages to conform to the operation of the adhesive applying means.
27. In a machine for labeling cylindrical packages having ways, means for supporting a label pack adjacent the ways so that the packages pass in rolling contact with the top label of the pack, means for applying pick-up adhesive causing the package to pick up the top label, means in the path of the packages at the front end of the machine for controlling said means, means for applying adhesive to the lap end of the outside label comprising a belt, a pulley for driving the belt, power operated means independent of the action of the cans for rotating the pulley, means for applying adhesive to the belt and means in the path of the packages for controlling the pulley driving means whereby the belt is advanced a single step as each package passes through the machine, presenting a newly coated portion of the belt to the label.
28. In a machine for labeling cylindrical packages having ways along which the packages are rolled, means for supporting a pack of labels adjacent the ways whereby each package passes in rolling contact with the top label, means for coating the front end of each outside label with adhesive, means in the path of the packages at the front end of the machine for controlling said means whereby the front of each label is coated as each package is admitted to the machine, means for coating the lap end of each outside label, means for driving said coating means and means in the path of the packages beyond the label table for tripping said means, and means at the front end of the machine for spacing the packages.
29. In a machine for labeling cylindrical packages, ways, a label support, power operated means controlled by the packages for applying adhesive to the labels and a gate for spacing the packages.
30. In a machine for labeling cylindrical packages, ways, a label support, power operated means controlled by the packages for applying adhesive to the labels, a gate for spacing the packages, and means over the gate for preventing the packages from jumping the gate.
31. In a machine for labeling cylindrical packages, ways along which the packages may be passed by rolling, means for supporting a pack of labels adjacent the ways so that the packages pass in rolling contact with the outside label, means actuated independently of the package for applying adhesive to each label as it comes to the outside of the pack and tripping means in the path of the packages controlling said applying means to operate the same in response to the passage of the packages through the machine, whereby each package is caused to pick up a label as it passes.
32. In a machine for labeling cylindrical packages, ways along which the packages may be rolled, means for supporting a pack of labels adjacent the ways so that the packages pass in rolling contact with the outside label of the pack, adhesive applying means causing each package to pick up a label as it passes, means for applying adhesive to the lap end of each outside label, means in the path of the packages for tripping said applying means causing same to operate in correspondence with the passage of the packages through the machine and means actuating

ed independently of the packages for presenting adhesive to said applying means.

33. In a machine for labeling cylindrical packages, ways along which the packages are rolled, means adjacent the ways for supporting a label pack, means for applying adhesive to the labels and causing them to be picked up by the packages as they pass, means beyond the label pack for pressing

10 the labels into position on the packages com-

prising a pad projecting into the path of the packages, and means for supporting the pad providing for adjustment of the same in the direction of the length of said path, said means comprising longitudinal supports into which the pads are fitted providing for their removal and rearrangement.

Signed by me at Baltimore, Maryland, this 23rd day of April, 1926.

CHARLES H. WILD.
